UNITED STATES PATENT OFFICE.

FRANK VOREL, OF ROY, MONTANA.

DESIGN FOR A SCREW.

51,291.

Specification for Design. Patented Sept. 18, 1917.

Application filed January 12, 1916. Serial No. 71,797. Term of patent 3½ years.

To all whom it may concern:

Be it known that I, FRANK VOREL, a citizen of the United States, residing at Roy, in the county of Fergus and State of Montana, have invented a new, original, and ornamental Design for a Screw, of which the following is a specification, reference being had to the accompanying drawing, forming part thereof.

Figure 1 shows a side elevation of my design.

Fig. 2 and Fig. 3 illustrate, respectively, front and rear views of the head.

Fig. 4 shows a plan view.

I claim:

The ornamental design for a screw as shown.

In witness whereof, I have hereunto subscribed my name this 20th day of December, 1915.

FRANK VOREL.
